UNITED STATES PATENT OFFICE

GEORGE D. MORRIS, OF NEW CASTLE, PENNSYLVANIA, ASSIGNOR TO NEW CASTLE
REFRACTORIES COMPANY, OF NEW CASTLE, PENNSYLVANIA, A CORPORATION OF
DELAWARE

TUNNEL-KILN CAR

Application filed August 27, 1928. Serial No. 302,232.

The present invention relates to the construction of the super-structure of kiln cars adapted for conveying material to be heat treated through continuous tunnel kilns.

5 Kiln car bodies are usually composed of a plurality of refractory blocks on which slabs of refractory material are positioned. A plurality of transverse girders of refractory material are positioned at longitudinally spaced 10 points on the refractory slabs and spaced apart to provide horizontal passages for the circulating kiln atmosphere. In kiln cars of the type to which the present invention is particularly applicable, a plurality of flat 15 slabs of refractory material are positioned on the transverse girders with the edge portions of each pair of adjacent slabs supported on one of the girders. The slabs are spaced closely together and serve as a support for the 20 material to be heat treated.

With certain classes of articles, it is necessary to provide a sand setting on the work supporting slabs due to the nature of the material being treated. In kiln operations of 25 this kind it has been found that the sand works down into the joints between the slabs and refractory blocks and when sufficient sand has collected in the joints, and the car is passed through the kiln, the sand expands and 30 tends to force apart the refractory blocks comprising the car body. Such expansion tends to rapidly destroy the car and is liable to cause the load to collapse.

To prevent infiltration of sand the joints 35 between the blocks are covered wherever possible. Practically, however, it is difficult to employ covered plates for the joints between the refractory slabs forming the loading deck of the car because such plates would interfere 40 with the setting of the ware.

The object of my present invention is to provide an improved construction and arrangement of the refractory elements composing the upper portion of the car body 45 which is characterized by the provisions for collecting and disposing of any sand filtering down between the joints of the refractory elements.

The various features of novelty which 50 characterize my invention are pointed out

with particularity in the claims annexed to and forming a part of this specification. For a better understanding of the invention, however, and the advantages possessed by it reference should be had to the accompanying 55 drawings and descriptive matter in which I have illustrated and described a preferred embodiment of the invention.

Of the drawings:

Fig. 1 is an elevation of a kiln car embodying my invention; 60

Fig. 2 is a perspective view of one of the girders;

Fig. 3 is an end elevation of a modified form of girder. 65

In the drawings and referring first to the construction shown in Figs. 1 and 2, A represents a metallic frame member forming the bottom of the car body and preferably made as a one piece steel casting. As shown the 70 frame member is provided with an upstanding marginal flange A'. The usual wheels B are journaled in the member A and the latter is provided as shown with a concrete filling C which extends to a level somewhat 75 below the upper edge of the marginal flange A'. Seated on the concrete layer C are a plurality of massive refractory blocks D. As shown there are four of these blocks and each of which extends the full width of the car. 80 Mounted on the tier of blocks D is a second tier of refractory blocks E. The blocks E are also substantially rectangular in outline and extend the full width of the car. As shown the blocks E are staggered with respect to the 85 lower tier of blocks so that each of the joints in the lower tier are covered by a block in the upper tier. A platform composed of large slabs H of refractory material is mounted on the upper side of the tier of blocks E. Each 90 of the slabs H is rectangular in outline and cross section and the slabs are positioned on the upper tier of blocks over the joints therein with their side edges in contact with one another.

Mounted on the corrugated upper surface of the platform H are a series of spaced apart transverse girders J each of which extends the full width of the car and is a one piece block of refractory material. As shown there are 105

five of these girders, J' , J^2 , J^3 , J^4 and J^5 and the girders J' and J^5 are located along the front and rear edges of the car respectively. The girders J^2 , J^3 and J^4 are positioned over the joints formed by the adjacent edges of the slabs H . The girders J' and J^5 may be of the usual I-beam form while the girders J^2 , J^3 and J^4 are of general H form with a longitudinal recess or groove J^6 semi-circular in cross section formed in the top surface thereof. A similar groove J^7 is preferably formed on the undersides thereof, although only one groove may be used as shown in Fig. 3.

A work supporting platform composed of large refractory slabs M rectangular in cross section and in outline is mounted on the transverse girders J . As shown in Figs. 1 and 2 there are four of such slabs along the length of the car with the slab edge portions supported on the flat upper surface of the girders J . The slabs are so arranged that the joint between the vertical side edge portions M' of each pair of slabs is positioned centrally of the groove J^6 of the corresponding supporting girder.

The present invention is particularly designed for use where the goods to be heat treated are set in sand distributed on the work supporting platform. With the present construction any sand which works down between the joints of the slabs M will fall into the grooves J^6 formed in the transverse girders. The grooves are of sufficient size to accommodate all of the sand which may drop during one passage of the car through the kiln. After the car is withdrawn from the kiln, the sand is removed from the grooves by means of a hook or vacuum pipe. The advantages of the lower grooves J^7 are that such grooves decrease the amount of material and weight of the girders and that the girders may be turned over when desirable to permit the grooves J^7 to act as the sand collecting means.

With this construction of the girders the edges of the slabs M can be made vertical which permits their reversal when the slabs begin to warp due to continued use. In this way the slabs have a longer useful life than in prior constructions where the slabs are generally formed with beveled edges. By supporting adjacent slabs on each of the girders, a greater cohesion of the work supporting platform is secured. The present invention is also adapted for use where more than one work supporting deck is used and the present arrangement for supporting the platform slabs provides a better support for the posts supporting the upper deck which are mounted along the joints between the slabs M .

While in accordance with the provisions of the statutes, I have illustrated and described the best form of embodiment of my invention now known to me, it will be apparent to those skilled in the art that changes

may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. A tunnel kiln car comprising a metallic bottom frame member, a refractory body portion mounted thereon, transverse girders mounted on said body portion and having a longitudinally extending recess in the top surface thereof, and a goods supporting platform consisting of a plurality of slabs supported by said girders, adjacent slabs being arranged with the joint therebetween positioned over one of said recesses.

2. A tunnel kiln car comprising a metallic bottom frame member, a refractory body portion mounted thereon, transverse girders mounted on said body portion and each having a longitudinally extending recess in the top surface thereof and a goods supporting platform consisting of a plurality of flat refractory slabs having vertical edge portions supported by said girders, adjacent slabs being arranged with the transverse joint therebetween positioned over one of said recesses.

3. A girder for a tunnel kiln car having a substantially flat upper supporting surface and a longitudinally extending recess formed in said surface.

4. A girder for a tunnel kiln car made of refractory material and having a substantially flat upper supporting surface and a longitudinally extending recess formed in said surface.

5. A girder for a tunnel kiln car made of refractory material and having substantially flat upper and lower surfaces and a longitudinally extending recess formed in each of said surfaces.

6. A refractory rail for supporting kiln car tops having a generally rectangular cross-sectional outline and having at least its top face grooved longitudinally from end to end thereof.

Signed at New Castle, in the county of Lawrence and State of Pennsylvania, this 23d day of August, A. D. 1928.

GEORGE D. MORRIS.
